PHOTOGRAPHIC COPYING MACHINE

Paul Landrock and Arthur W. Caps, Rochester,
N. Y., assignors to Photostat Corporation, Providence, R. I., a corporation of Rhode Island

Application October 6, 1942, Serial No. 460,972

13 Claims. (Cl. 88—24)

1

This invention relates to photographic machines, or cameras, for making reproductions of papers, records and the like, one of its objects being to provide such a machine having a more simple and efficient construction for making copies of such articles in a more rapid and convenient manner.

There are many situations in which the bulk of articles to be copied are papers of substantially uniform or, at least restricted dimensions, and another object is the provision of a more convenient and efficient machine specially adapted for such work.

Another object is to provide such a machine in the form of a desk-like article of furniture.

A further object is to provide a machine of the character described having operating and controlling mechanism of a simple but more automatic nature, capable of producing copies more rapidly and with less labor.

Still a further object is the provision of a machine by which the above advantages are made conveniently available for copying either one or both sides of an object, and for making reproductions on one side of ordinary film or on both sides of a duplex film, as may be desired, with a minimum of manipulation of the film and of movement by the operator.

To these and other ends the invention resides in certain improvements and combinations of parts, all as will be hereinafter more fully described, the novel features being pointed out in the claims at the end of the specification.

In the drawings:

Fig. 1 is a top plan view of a copying machine embodying the present invention;

Fig. 2 is a similar view, with parts removed for better illustration;

Fig. 3 is a front elevation;

Fig. 4 is an end elevation, partly broken away;

Fig. 5 is a sectional elevation on the line 5a—5a in Fig. 2;

Fig. 6 is a sectional elevation on the line 6a—6a in Fig. 3;

Fig. 7 is a sectional plan view, substantially on the line 7a—7a in Fig. 6;

Fig. 8 is an enlarged, sectional elevation on the line 8a—8a in Fig. 6;

Fig. 9 is an enlarged, horizontal section through the mechanism for actuating the film feeding and severing means, substantially on the line 9a—9a in Fig. 6;

Fig. 10 is an elevation, substantially as viewed from the bottom in Fig. 9, with parts broken away;

2

Fig. 11 is an enlarged detail view of the yielding driving connection to the severing means, as shown at the left in Fig. 9;

Fig. 12 is an elevation, substantially as viewed from the top in Fig. 9, showing the parts rotated through one-half a cycle during actuation of the feeding means;

Fig. 13 is a similar view showing the parts rotated through three-quarters of a cycle during actuation of the severing means;

Fig. 14 is a similar view showing the parts returned to initial position;

Fig. 15 is a top plan view of the parts as shown in Fig. 14;

Fig. 16 is a top plan view of the mechanism for actuating the film conveyor;

Fig. 17 is a sectional elevation of the same;

Fig. 18 is an elevation substantially on the line 18a—18a in Fig. 16;

Fig. 19 is a sectional view of the parts shown in Fig. 18 on line 19a—19a thereof;

Fig. 20 is a sectional elevation of an electric switch employed in the mechanism;

Fig. 21 is a top view of the same, and

Fig. 22 is a schematic diagram of the electric circuits employed.

In the embodiment of the invention herein disclosed by way of illustration, the copying machine is compactly and conveniently combined with a desk-like article of furniture, having in common therewith the same table-like, work supporting surface, housing walls and supports. The dimensions of such parts are preferably substantially the same as those of the ordinary flat top desk, comprising a substantially horizontal, work supporting surface 30, Fig. 1, with four side walls, carried by standards or legs, indicated at 31, Fig. 3. The front wall 32 preferably has the usual reentrant portion 33, Figs. 3 and 4, to accommodate the knees of an operator seated at the desk and the end and rear walls are preferably plain. The front wall adjacent its ends preferably accommodates a number of drawer compartments, as indicated at 34, Fig. 3.

The work supporting surface 30 comprises a pair of transparent portions 35 and 36, Fig. 1, substantially flush therewith, which serve also as the object supporting surfaces of the camera. These surfaces are preferably formed by plates of glass or other transparent material set in openings in the surface 30 and each equipped with slightly raised, rectangular, marginal portions 37, reversely arranged as shown, to serve as guides for accurately locating on these object holders the sheets or other items to be copied.

45
50
55

A central panel 38, Figs. 5 and 6, is preferably of separate construction supported along its rear side by hinges and by stop links 39 and at its forward side on the cleat 40, this panel being adapted to swing up and rearwardly to afford access to the film supply means hereafter described.

An object placed face downwardly on one of the holders, 35 or 36, has its face illuminated by lamp means within the housing, as hereafter described, and the downwardly projected image of its face is reflected through lens means into the focal plane of the camera, by reflecting means located directly below each object holder and on opposite sides of the intermediate focal plane. These optical means are the same for the two object holders, so that a description of one will apply to both. The reflecting means comprises, in the present instance, a glass prism 41 (Fig. 5), of any known or suitable construction, located vertically below the center of the object holder. The image from the object holder is reflected horizontally by the prism toward the intermediate focal plane, as well understood in the art, and preferably through a lens or system of lenses, of known construction, arranged to project and focus the image on one side of a film supported in the focal plane, indicated at 42. This same optical system is employed under each object holder, for use either separately with single coated film or for projecting images on opposite sides of the same sheet of double coated or duplex film. Each prism 41 and its lens system are associated with a lens tube 43, Fig. 8, mounted on the camera front, 44, connected by a bellows 45 with an opening 46 in the front wall 47 of the camera dark chamber. A shutter 48 is pivotally associated with the camera front and operated by means hereafter described.

The sensitized film 49 is supported and guided at its opposite sides in the focal plane by spaced, upright, channel-shaped guides 50, Figs. 6 and 8, fixed at their bottoms on shoes 51 slotted to engage an upper edge portion of a frame 52 for supporting the film feeding means and secured thereto by means of a clamping screw 52a so as to be adjustable transversely to closely fit the edges of the film.

The film supply means preferably comprises a spool 53, Fig. 8, rotatably mounted on rollers 54 in a casing 55 fixed to and above the top 56 of the dark chamber. The film is carried from the spool over a guide roll 57, downwardly between guide plates 58 extending through an opening in the bottom of casing 55 adjacent the upper ends of the film guides 50 of the dark chamber. The guide plates 58 are preferably apertured, as at 59, to receive a contact member 60 of any known or suitable splice indicating mechanism such, for example, as disclosed in Landrock Patent 2,109,373, but forming no part of the present invention. The film spool 53, or guide roll 57, may be provided with any known or suitable frictional means for retarding the feed of the film and maintaining it taut in the focal plane, as well understood in the art.

The film feeding means may be of known or any suitable character comprising, in the present instance, the usual pair of opposed feed rolls 61 and 62, located within frame 52, and arranged to engage the opposite sides of the film below the guides 50. The ends of roller 61 are journaled in the upper ends of a pair of arms 63 pivoted at their lower ends 64 on the front and rear walls of frame 52. Each of these arms has

fixed thereto a lever 65, biased by a spring 66, so as to press roller 61 toward roller 62 to afford the desired feeding pressure against the film. Each lever 65 extends adjacent a flattened cam surface 67 (Fig. 9) of a rod 68, journaled adjacent its ends in casing 52, and having at one end a finger lever 69 (Fig. 7), by means of which the rod may be oscillated to lift lever 65 and move roll 61 away from roll 62, to facilitate the insertion or removal of the film. Below the rolls is an opening in frame 52 through which the film may be fed past the severing means and into the film conveying means hereafter described.

The film severing means may be of known or any suitable variety, comprising, in the present instance, a stationary shear bar 70, Fig. 8, on frame 52 with which cooperates a knife blade 71, Fig. 9, on a frame 72 reciprocating in guides on frame 52 toward and from the shear bar. The knife frame 72 comprises extended side rails formed with rack teeth 73, with which cooperate gear sectors 74 fixed on a shaft 75 journaled at its ends in side wall portions of frame 52. A spring 76 is arranged to rotate shaft 75 to retract knife blade 71. Shaft 75 has its rear end 77 extended for connection with the actuating mechanism hereafter described.

The above film feeding and severing means are actuated in coordination with each other by a common mechanism, which will now be described. The electric motor for this mechanism is indicated at 78 (Figs. 2 and 7), mounted on a rear portion of the floor of the housing. This motor drives, through suitable gearing (not shown) a shaft 79 extended for connection with a gearing unit, indicated generally at 80 (Figs. 6 and 7), and shown in detail in Figs. 9 to 15, inclusive. Referring first to Fig. 9, drive shaft 79 has fixed thereon a bevel gear 81 meshing with a similar gear 82 on a shaft 83 journaled in suitable bearings, preferably of the ball or roller type, in the front and rear walls 84 and 85, respectively, of a supporting frame for the gearing unit.

Fixed on shaft 83 is a spur gear pinion 86, meshing with a gear 87, fixed on a shaft 88, similarly journaled in the frame and extended at its rear end to support and drive a crank arm 89. Rotatably connected to crank 89 is a pitman 90, having at its opposite end a slot 91, slidably embracing a trunnion 92 fixed in a driven crank arm 93. Trunnion 92 carries a pin 94 to which is connected a coil tension spring 95, fixed at its opposite end of the pitman, this spring tending to hold trunnion 92 against the inner end of bearing slot 91 of the pitman. Crank 93 is fixed on the extended rear end of a shaft 96 journaled in the unit frame and the crank is positively oscillated in an anti-clockwise, driving direction by engagement therewith of the inner end of the slot in the pitman, as shown in Fig. 12. On the return stroke of the pitman, the crank is oscillated idly in a clockwise direction by the tension of spring 95, as shown in Fig. 13, until an extended lug 97 on the crank strikes an adjustable stop screw 98 on the frame, as shown in Fig. 14. The adjustable stop thus determines the initial position and length of working stroke of the crank.

Shaft 96 has fixed thereon a notched disk 99 (Figs. 9 and 10), forming one-half of a one-way clutch, of known or suitable construction. In the present instance, disk 99 is formed with a series of spaced, circumferential, cam-shaped notches 100, housing spring pressed rollers 101 which roll along the inclined cam bottoms of the

notches into and out of driving engagement with the inner periphery of a ring 102 fixed on the forward face of a spur gear 103 rotatably mounted on shaft 96 and meshing with a pinion 104 fixed on a shaft 105, journaled at its ends in the frame. Shaft 105 has fixed thereon a spur gear 106 meshing with a pinion 107 fixed on a shaft 108 journaled at its ends in the frame and having its forward end extended and detachably clutched to a sleeve 109 rotatably mounted on the rear wall of the camera chamber. The other end of sleeve 109 is detachably clutched at 110 to the rearwardly extended trunnion of feed roll 62 for driving the same. This roll and its connected shaft 108 are held against rotation in a reverse direction to maintain the tension on the film, by means of a one-way clutch similar to that described above and indicated at 110a, Figs. 9 and 10.

It will be apparent from the above construction that as the motor rotates crank 89 and oscillates pitman 90 from initial position to the position shown in Fig. 12, clutch part 99 is oscillated in an anti-clockwise direction to positively engage the other half of the clutch, or gear 103, to positively rotate feed roll 62. As pitman 90 moves to the right, as shown in Fig. 13, crank 93 is oscillated in a clockwise direction until its lug 97 strikes stop 98 against which it is held by spring 95 as trunnion 92 moves to the left in the pitman slot, as shown in Fig. 14. In this direction of motion, clutch rollers 101 disengage and leave gear 103 stationary. But the position in which crank 93 is arrested by stop 98 determines the length of the next positive stroke of crank 93 in the opposite direction and hence the amount of rotation of the feed rolls and the distance through which the film is fed.

The severing means or film cutting knife is actuated by the above gearing unit by means comprising a pair of spaced wrist pins 111 on the rear face of gear 87, arranged to engage spaced edge surfaces 112 and 113 on a crank arm 114, rotatably mounted on and yieldably connected to a shaft 115, Figs. 9 to 15, inclusive. To this end, arm 114 is carried by a hub 116, rotatably mounted on shaft 115, and has fixed thereto one end of a coil tension spring 117, the other end of which is fixed to a collar 118, fixed on shaft 115. Hub 116 is formed at its forward end with a trailing abutment 119 with which engages an opposing abutment 120 on collar 118. These abutments are normally pressed together by spring 117, which is relatively stiff and transmits the actuating force to the knife. In the event, however, that the cutting stroke of the knife should be obstructed, as by some disarrangement or accumulation of film or the like, spring 117 will yield and abutment 119 will move away from abutment 120, without further cutting actuation of the knife. The rear end of shaft 115 has fixed thereon a pulley 121, on which is wound a coil tension spring 122 (Figs. 12 to 14, inclusive), one end of which is fixed to the pulley and the other to the frame, the action of this spring being to co-operate with spring 76 to normally hold arm 114 in its lowermost position (Fig. 12), and the knife retracted. It will be understood that actuating spring 117 is stiff enough to overcome the opposition of retracting springs 76 and 122. The forward end of shaft 115 is detachably clutched to a sleeve 123, journaled in the rear wall of the camera chamber and having its other end detachably clutched to the trunnion of knife actuating shaft 75 (Fig. 9). It is apparent from the above construction (Fig. 13) that as gear 87 is ro-

tated by the motor, its wrist pins 111, after actuation of the feed rolls, engage crank arm 114 and, through spring 117, yieldably advance the knife to cut the film.

5 The conveying means for the severed film comprises preferably an extension of the bottom of the camera chamber by a housing portion 124 (Figs. 3, 5, 6 and 8). This extension lies under the main housing, with one end under the film severing means and the other projecting toward the left of the housing, as shown in Fig. 3, to convey the severed film to any suitable receptacle, indicated generally at 125. The main bottom wall 126 of the housing is formed below the feeding and severing means with a slot 127 and the conveyor housing portion 124 has in its upper wall a registering slot 128. Guides 129 guide the film, as it is fed downwardly for cutting, so that its forward edge is directed between spaced upper and lower conveyor belts 130 and 131, carried by pulleys 132 and 133, journaled at their ends in suitable bearings adjacent the front and rear side walls of housing portion 124. Preferably a series of such pulleys 132 are fixed on an upper shaft 134 and a series of pulleys 133 on the lower shaft 135 (Figs. 16 and 17) and the conveyor belts are supported at their opposite ends by similar pulleys and shafts, indicated generally at 136 and 137 (Fig. 3).

20 The rear ends of the pulley shafts are connected by intermeshing gears 138 and 139 for uniform rotation in opposite directions and the rear end of shaft 134 is detachably pinned, as by means of a slotted sleeve 140 (Figs. 17 and 19) to one 25 of a shaft 141, journaled at its ends in opposite sides of a frame 142 which supports a unitary gearing system for driving the conveyor. Frame 142 is fastened by any suitable means to a rear wall 143 of the conveyor housing portion, as best 30 shown in Fig. 17, and is driven by an electric motor 144, fixed on an extension 145 of the bottom wall of the conveyor housing portion. The conveyor driving gearing preferably comprises a spur gear pinion 146 (Figs. 18 and 19), fixed on shaft 35 141 meshing with a gear 147, fixed on a shaft 148, journaled at its ends in the frame. Shaft 148 is extended at its rear end and detachably pinned, as at 149 (Fig. 17), to a shaft 150 driven by suitable connection with the shaft of the motor 40 144. Shaft 148 has fixed thereon also a spur gear pinion 151, meshing with a gear 152, fixed on a shaft 153, journaled in the frame, and the gear carries a wrist pin 154 for actuating an electric switch included in the circuit of the motor for 45 stopping the same in initial position after each 50 complete revolution of the gear 152, as hereafter explained in connection with the main electric circuit means, which will now be described.

55 The electric circuit means for operating and controlling the feeding and severing means preferably comprises a normally closed switch in the motor circuit, positioned for engagement and actuation by a part on the associated gearing which automatically opens the circuit when such 60 part returns to initial position after one complete cycle of operation of the feeding and severing means. The motor circuit also includes a manually operable switch, conveniently located on the work supporting surface and connected 65 to short-circuit the switch which is opened by the motor so that, when it is manually operated, the circuit is closed and the motor is energized, until its driven part returns to initial position at the 70 end of the cycle and engages and opens the switch for stopping the motor in initial position. Just

before completing its cycle, the same part engages and operates a second and normally open switch in the circuit of the conveyor motor for automatically starting it, to convey away the severed film, and the conveyor motor drives a part arranged to engage a third and normally closed switch so as to open its own circuit and stop itself on return to initial position.

The manually operating starting switch is preferably in the nature of a simple push button, of any known or suitable variety, conveniently located on the work surface or desk top, as indicated at 155 (Fig. 1). This switch controls a circuit comprising a cable 1 (Fig. 22) which leads to one terminal of the motor 78 for the feeding and severing means. The other terminal of the motor is connected through a lead 4 to the positive side of the line connection indicated generally at 156. The circuit controlled by button 155 comprises also a cable 3, with which it is connected by a main switch 157, which remains closed while the machine is in use. Cable 3 leads directly to the other, or negative side of the line, and it will thus be seen that depression of button 155 completes the circuit through the motor to start actuation of the feeding and severing means, so long as main line switch 157 is closed.

Push button 155, as stated, serves to temporarily bridge a switch in the circuit of the motor for the feeding and severing means which is normally closed but is automatically held open by the motor in its initial or starting position. To this end, driving crank 89 has fixed thereon an arm 158 (Fig. 14), formed with a slot 159. Rotatably mounted on the hub of the crank is a part 160 carrying a set screw 161 by which it is clamped to arm 158 for adjustment circumferentially to vary the time of opening of the switch. In the initial or starting position of the part 160, its outer end engages and holds up the outer end of a leaf spring 162, fixed at its other end on the casing of a switch 163. Switch 163 may be of any known or suitable single throw, quick-acting type, comprising in the present instance, a commercially available article known as a "micro switch," and sold by the Micro Switch Corporation of Freeport, Illinois, as disclosed in Patent No. 1,960,020. This switch comprises a terminal 164 leading to one end of a contact plate 165 of spring metal, the other end of which carries a contact button 166 normally engaging a conducting bar 167 of a terminal 168. A plunger 169 is depressed by spring 162 to press at its lower end against the spring plate 165 and overcome its inherent tension so as to cause its button 166 to snap quickly down into contact with a plate 170 carried by a terminal 171. Switch 163 has its terminal 164 connected, as shown, by a branch of cable 1 with one terminal of motor 78, the other terminal of which is connected with the power line. Terminal 168 of the switch is connected, as shown, by a branch of cable 2 through the main switch 157 with the other side of the power line, so that the switch normally closes the circuit through the motor. The other terminal 171, however, is unconnected and when motor 78 is in starting position, its driven part 160 holds the switch contact 166 against the unconnected terminal 171 so as to hold the circuit open. Upon the momentary bridging of this switch by the manually operated button 155, however, the motor starts, the part 160 releases spring 162 so that contact button 166, actuated by the spring plate 165, snaps back into contact with bar 167 of terminal 168 and the switch remains closed throughout the cycle of the

motor until its part 160 returns again to starting position and opens the switch.

Motor 78 of the feeding and starting mechanism, as stated, automatically closes the circuit of the conveyor and this is preferably accomplished by arranging a second, quick-acting switch 172, Fig. 14, such as described above, so that just before part 160 returns to starting position, it momentarily engages its actuating spring 173. In this case, terminal 168, normally engaged by contact 166, is unconnected and terminal 171 is connected through one branch of a cable 6 with one terminal of conveyor motor 144, the other terminal of which is connected by a branch of cable 4 with one side of the power line.

When switch 172 is operated by the motor for the feeding and severing means, therefore, the circuit is closed to start the conveyor motor after completion of the film severing operation. To

stop the conveyor motor upon the completion of its cycle, a third switch 174 of the same quick-acting variety is employed (Figs. 16, 18 and 19) and so arranged that its spring 175 is engaged by the wrist pin 154 of gear 152 which is driven by the conveyor motor, as previously described. Terminal 164 of the switch is connected by a branch of cable 2, through the main switch 157, with cable 3 which leads to the negative side of the line. Terminal 171 is unconnected, while terminal 168 is connected by cable 6 to one terminal of the conveyor motor, the other terminal of which is connected by cable 4 with the other or positive side of the line. This switch is mechanically opened, however, by wrist pin 154, as stated, when the conveyor motor is in initial or starting position and is bridged to start the motor by switch 172 operated by the motor of the feeding and severing means when about to complete its cycle.

The downwardly turned face of an object on each of the object holding surfaces 35 and 36 is illuminated through these transparent surfaces by lamp means in the housing below, preferably of the fluorescent tube variety. The main illumination is preferably provided by a pair of such lamps 176, on either side of the object holder, and mounted on casings 177 on an auxiliary partition 178, these parts being the same for both object holders. Casing 177 is conveniently employed to hold any operating means for the lamp and also to support reflecting shields 179 for confining the illumination to the transparent portions 35 and 36. Similar lamps 180 are similarly supported on the other two sides of the transparent portions 35 and 36 and similarly equipped with reflecting shields 181. The circuits for these lamps are connected through cables 2 and 4 to opposite sides of line, when main switch 157 is closed.

The means for actuating each of the camera shutters 48, referred to above, preferably comprises a solenoid 182 (Fig. 5), the core 183^a of which is connected to one end of a flat steel band 184, wound around a pulley 185 fixed on an extension of a pivotal spindle 186 of each shutter.

A coil spring 187 is preferably wound around and secured at one end to the pulley and fixed at its opposite end, so that, upon actuation of the solenoid, core 183^a is retracted to turn the pulley and swing the shutter to the open position, shown in dotted lines in Fig. 8, against the tension of spring 187, which serves to close the shutter upon opening of the circuit. The circuit, as indicated at 188 (Fig. 22), includes a time switch 188, preferably located on the work supporting surface or desk top. Any known or suitable time switch

may be employed for this purpose having a series of positions with which the switch handle may be selectively registered, against the tension of a spring, so that upon release, the switch handle closes the circuit while returning to starting position for a period of time corresponding in length to the selected distance through which the handle is moved, as well understood in the art. A separate time switch is provided for each shutter, as shown, and one of them, as at the right in Fig. 1, is closely associated with the starting switch 155 and the main switch 157, for convenient assembly of the control.

The operation of the machine is apparent from the above description of the construction. Either single or double coated film may be employed, as desired. Main switch 157 is closed, thereby energizing the lamp circuits. Either or both of the object holders 35 and 36 may be utilized, as the case may be, the objects being accurately located face down thereon with their edges against the guides 37. Either or both of the time switches 183 are correspondingly operated to effect suitable exposures, and button 155 is then depressed to bridge switch 163 and start motor 78 of the feeding and severing mechanism.

When the motor starts, part 160 releases spring 162 of the switch which thereupon quickly closes, after which button 155 may be released. The exposed film is thus fed downwardly through the severing knife, a distance regulated by the adjustment of stop screw 98, and pins 111 then operate crank 114 to actuate the severing knife. Thereafter part 160 presses momentarily against spring 173 to close switch 172, which bridges switch 174 and energizes the conveyor motor. The starting of the latter carries pin 154 out of contact with spring 175 of switch 174 which thereupon maintains the circuit closed while the film is conveyed to the receptacle 125, after which pin 154 again engages spring 175, opens switch 174 and stops the conveyor motor and the machine is thereby ready for the next exposure.

The invention affords the facilities of a desk, with its ample work supporting surface and drawer compartments, in combination with a copying machine having all of its object holders and controlling means conveniently located in the same work supporting surface. The work to be copied may be assembled on the work surface 30 and the operator may sit thereat and sort, or otherwise arrange the same, the selected papers being placed on the object holders and the machine controls actuated, all within easy reach of the operator, so that copies may be made and delivered to the receptacle 125, or other desired destination, with a minimum of time and effort. At the same time the mechanisms for operating the various parts are comparatively simple and reliable in operation and inexpensive to manufacture.

The invention thus accomplishes its objects and while a preferred embodiment has been herein disclosed in detail, such disclosure is intended to be illustrative, rather than limiting, as it is contemplated that various modifications in the construction and arrangement of the parts will occur to those skilled in the art, within the spirit of the invention and the scope of the appended claims.

We claim:

1. A photographic machine comprising a housing with a table-like top having therein an exposure opening covered by a transparency adapted to have an object manually placed in and re-

moved from exposure position thereon, a camera in said housing having a focal plane and means for projecting on said plane the image of an object transmitted downwardly through said transparency, film supply means, film feeding and severing means, a first circuit including a motor for actuating said feeding and severing means, a conveyor for delivering the severed film from said housing, a second circuit including a motor for driving said conveyor, manually operable means for controlling said first circuit, and means operated by said first circuit for controlling said second circuit including said conveyor motor.

2. A photographic machine comprising a housing of generally desk shape having a substantially flat top with an exposure opening therein covered by a transparency, a camera in said housing having a focal plane and means for projecting thereon the image of an object sheet transmitted downwardly through said transparency, roll means for holding film, film feeding means located below said focal plane for drawing film by tension therethrough, film severing means, a conveyor for delivering the severed film from said housing, an electric circuit comprising motor means for actuating said feeding and severing means, and an electric circuit including a driving motor and a switch operated by said motor means for driving said conveyor after operation of said severing means.

3. A photographic machine comprising a housing having a table-like, top work surface with a window therein covered by a transparency adapted to freely support a work sheet to be copied, a camera in said housing, film supply means, film feeding and severing means, film conveying means for delivering the severed film from said housing, an electric circuit comprising motor means for actuating said feeding and severing means, a manually operable starting switch for controlling said first electric circuit, a second electric circuit comprising a driving motor for actuating said conveying means, and switch means actuated by said motor means for controlling said second electric circuit to actuate said conveying means.

4. A photographic machine comprising a housing having a table-like, top work surface with a window therein covered by a transparency adapted to have paper sheets and like objects manually placed in and removed from face-down, exposure position thereon, a camera in said housing having a focal plane and means for projecting in said plane the image of an object sheet transmitted downwardly through said transparency, film supply means, film feeding means, means for severing portions of said film successively exposed in said focal plane, film conveying means, a first electric circuit comprising motor means for successively actuating said feeding and severing means, a second electric circuit comprising a driving motor for actuating said conveying means, a normally closed switch in said first circuit arranged for operation by said motor means in initial position to open said circuit, a normally open switch in said second circuit arranged for operation by said motor means, to close the same after operation of said severing means, a normally closed switch in said second electric circuit arranged for operation by said driving motor for opening said second circuit to stop said conveying means, and a manually operable switch for closing said first circuit to start the operation of said motor means.

5. A photographic machine comprising a housing having a table-like, top work surface with a window therein covered by a transparency adapted to have a work sheet manually placed in and removed from face-down, exposure position thereon, a camera in said housing having a focal plane and means for projecting in said plane the image of an object sheet transmitted downwardly through said transparency, feed rolls for feeding a film in said plane, film severing means, a rotary element, an electric motor for driving said element, a connection between said element and said feed rolls for rotating the same, a connection between said element and said severing means for actuating the same after operation of said feed rolls, a part on said rotary element, a normally closed switch in the circuit of said motor arranged to be engaged and opened by said part for stopping said element in initial position, and manually operable switch means for closing said circuit to start said element.

6. A photographic machine comprising a housing having a desk-like, top work surface formed with a window closed by a transparency adapted to support an object sheet, a camera in said housing having an upright focal plane and means for projecting in said plane an image of said sheet transmitted downwardly through said transparency, roll means for supplying film, feed rolls below said plane for feeding a film downwardly therethrough, film severing means, a conveyor for delivering the severed film outside said housing, a motor for driving said conveyor, a rotary element, a motor for driving said element, connections between said element and said feed rolls and severing means for actuating the same in succession, a part on said rotary element, a normally open switch in the circuit of said conveyor motor arranged to be engaged and closed by said part for starting said conveyor motor after operation of said severing means, a normally closed switch in the circuit of said element motor arranged to be engaged and opened by said part for stopping said element in initial position, means actuated by said conveyor motor for opening the circuit thereof and stopping the same, and manually operable means for closing the circuit of said element motor to start the same.

7. A photographic machine comprising a housing with a table-like, top work surface provided with spaced windows therein covered by transparencies arranged to have object sheets manually placed in and removed from face-down, exposure positions thereon, means in said housing for illuminating said sheets through said transparencies, a camera in said housing having a focal plane and a pair of lens means each having an axis normal to said plane and reflecting means for receiving images of said sheets transmitted downwardly through said transparencies, respectively, and reflecting the same through said lens means against opposite sides of the film in said plane, independently operated shutter means for each of said lens means, film supply means, film feeding means, means for severing and separating the portions of film successively exposed in said plane, an electric circuit including motor means for actuating said film feeding and severing means, and switch means located on said work surface for controlling said circuit.

8. A photographic machine comprising a housing with a table-like, top work surface having therein a pair of spaced transparent portions adapted to have object sheets manually placed in and removed from face-down, exposure positions thereon, means in said housing

in and removed from exposure positions thereon, means in said housing for illuminating said sheets through said portions, a camera in said housing provided with lenses arranged on opposite sides of the focal plane thereof with their axes normal thereto and with spaced reflecting means for receiving images of said sheets transmitted downwardly through said portions and reflecting the same through said lenses, respectively, against opposite sides of a film in said plane, a shutter for each of said lenses, an electric circuit including a motor for actuating each of said shutters, film supply means, film feeding and severing means, an electric circuit including a motor for actuating said feeding and severing means, a time switch located on said work surface for independently controlling each of said shutter circuits, and a switch on said work supporting surface for controlling said circuit for said feeding and actuating means.

9. A photographic machine comprising a housing with a substantially horizontal top work surface provided with a pair of spaced transparent portions adapted to have object sheets manually placed in and removed from exposure positions thereon, a camera in said housing having a lens on each side of the focal plane thereof, means for receiving images of said sheets transmitted downwardly through said portions and reflecting the same through said lenses against opposite sides of the film in said plane, respectively, film supply means above said plane, film feeding and severing means below said plane, film conveying means below said severing means, an electric circuit including a motor for actuating said feeding and severing means, an electric circuit including a motor for actuating said conveyor means, a switch on said work surface for controlling the circuit on said feeding and severing means, and a switch actuated by the motor for said feeding and severing means for controlling said conveyor means circuit.

10. A photographic copying machine comprising a housing with a table-like, top work surface provided with a pair of spaced transparent portions adapted to support object sheets in exposure position thereon, a camera in said housing having an upright focal plane and a lens on each side thereof, means for receiving images of said sheets transmitted through said portions and reflecting the same through said lenses, respectively, against opposite sides of a film in said plane, roll means for supplying film, film feeding and severing means below said plane, conveying means for delivering film outside said housing, an electric circuit including a motor for actuating said feeding and severing means, an electric circuit including a motor for actuating said conveying means, a switch on said work surface for closing the circuit of said motor for said feeding and severing means to initiate actuation thereof, an electric switch arranged for operation by said motor for said feeding and severing means for closing the circuit of said conveying means motor to initiate actuation thereof after the severing of the film, and a switch arranged for actuation by each of said motors for opening the circuit thereof to stop the same upon completion of the cycle of said parts actuated thereby.

11. A photographic machine comprising a housing with a table-like, top work surface provided with spaced windows therein covered by transparencies arranged to have object sheets manually placed in and removed from face-down, exposure positions thereon, means in said housing

for illuminating said sheets through said transparencies, a camera in said housing having a single upright focal plane and a pair of lens means each having an axis normal to said plane and prism means for receiving images of said sheets transmitted downwardly through said transparencies, respectively, and reflecting the same through said lens means against opposite sides of a double-coated film in said plane, independently operated shutter means for each of 10 said lens means, means for supplying a double-coated film, film feeding means for feeding a predetermined length of film from said supply means through said focal plane, means for severing and separating the lengths of film successively 15 exposed in said plane and means for actuating said film feeding and severing means.

12. A photographic machine for making copies of paper sheets and the like on opposite sides of double-coated sensitive film, comprising a housing having a table-like, top work surface provided with spaced windows therein covered by transparencies arranged to have object sheets manually moved to and from face-down, exposure positions thereon, guide means on adjacent sides of said windows, respectively, for alining said sheets therewith, means in said housing for illuminating said sheets through said transparencies, a camera in said housing having a focal plane and a pair of lens means each arranged with its axis normal to said plane, reflecting means for receiving images of said sheets transmitted through said transparencies, respectively, and reflecting the same through said lens means against opposite sides of a double-coated film in 35 said plane, means in said housing for supplying a double-coated film, film feeding means for feeding a length of film from said supply means through said plane, film severing means for separating from said film the successively exposed lengths thereof, electric circuit means including motor actuating means in said housing for said film feeding and severing means, and switch means accessibly located on said housing for controlling said motor actuating means.

13. A photographic machine for making copies of paper sheets and the like on opposite sides of double-coated sensitive film, comprising a housing provided with a table-like, top work surface having spaced windows therein covered by transparencies adapted to have object sheets manually moved to and from face-down, exposure 50 position thereon, means in said housing for il-

luminating the under surfaces of said sheets through said transparencies, a camera dark chamber in said housing having therein an upright focal plane and means for projecting on opposite sides thereof the images of said sheets, respectively, means in said housing between said work surface thereof and said chamber for supplying a double-coated film, said work surface having an opening therein between said windows and a movably connected cover section providing access to said film supply means, film feeding means for feeding a predetermined length of film from said supply means through said focal plane, film severing means for separating from said film the successive lengths thereof exposed in said plane, electric circuit means including motor actuating means in said housing for actuating said feeding and severing means and switch means accessibly located on said housing for controlling said motor actuating means.
